(57) **CLAIM**

The ornamental design for a clothes hanger, as shown and described.

DESCRIPTION

FIG. 1 is a perspective view of the clothes hanger of the present design in a fully extended position.

FIG. 2 is an elevation view of one side of the clothes hanger of FIG. 1.

FIG. 3 is an elevation view of another side of the clothes hanger of FIG. 1.

FIG. 4 is an elevation view of another side of the clothes hanger of FIG. 1.

FIG. 5 is an elevation view of another side of the clothes hanger of FIG. 1.

FIG. 6 is a top plan view of the clothes hanger of FIG. 1.

FIG. 7 is a bottom plan view of the clothes hanger of FIG. 1.

FIG. 8 is a perspective view of the clothes hanger of the present design in a fully collapsed position.

FIG. 9 is an elevation view illustrating an alternate position of the clothes hanger of FIG. 1; wherein the top tier arms are shown collapsed and the bottom tier arms are shown extended.

FIG. 10 is an elevation view illustrating an alternate position of the clothes hanger of FIG. 1; wherein the top tier arms are shown extended and the bottom tier arms are shown collapsed.

FIG. 11 is an elevation view illustrating an alternative position of the clothes hanger of FIG. 1; wherein the top tier arms and post are shown extended and the bottom tier arms are shown collapsed; and,

FIG. 12 is an elevation view illustrating an alternative position of the clothes hanger of FIG. 1; wherein the top tier arms and post are shown extended and the bottom tier arms are shown extended.

The broken lines on the top edges of the arms in FIGS. 1-6 and 8-12 and the broken lines in FIG. 7 depict unclaimed portions of the design.

1 Claim, 8 Drawing Sheets
